United States Patent Office

Des. 221,684

Patented Aug. 31, 1971

221,684

TEMPLATE

Edward P. Martel, Waterford, and Derek R. Evans, Delmar, N.Y., assignors to The Bendix Corporation

Filed June 30, 1970, Ser. No. 23,773

Term of patent 14 years

Int. Cl. D10—99

U.S. Cl. D52—6

FIG. 1.

FIG. 2

FIG. 1 is a top plan view of a template showing our new design; the opposite side being a mirror image thereof; and

FIG. 2 is a side elevational view of FIG. 1 as taken from the lowermost point.

We claim:

An ornamental design for a template, as shown and described.
